US0D1061474S

(12) **United States Design Patent** (10) Patent No.: **US D1,061,474 S**
(45) Date of Patent: ** Feb. 11, 2025

(54) **HEADPHONES**

(71) Applicant: **Shenzhen Yiboyi Industrial Co., Ltd.**,
Shenzhen (CN)

(72) Inventor: **Hailong Huang**, Shenzhen (CN)

(***) Term: **15 Years**

(21) Appl. No.: **29/892,044**

(22) Filed: **May 12, 2023**

(51) LOC (15) Cl. **14-01**

(52) U.S. Cl.

USPC **D14/205**

(58) Field of Classification Search

USPC D14/205; D29/112; 2/209;
381/380-381, 370, 374

(57) **CLAIM**

The ornamental design for a headphones as shown and described.

DESCRIPTION

FIG. 1 is a perspective view of a headphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the headphones that form no part of the claimed design.

1 Claim, 8 Drawing Sheets
